(57) **CLAIM**

The ornamental design for an air outlet cover for an automobile, as shown and described.

DESCRIPTION

FIG. 1 is a front, perspective view of an air outlet cover for an automobile of our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The present design includes a mirror image of the design depicted that is not shown.
